UNITED STATES PATENT OFFICE

JOHN J. CISLER, OF NILES, MICHIGAN

CLOSURE CHECK AND RETENTION DEVICE

Application filed March 31, 1930. Serial No. 440,439.

This invention relates to improved device which is constructed to function as a check and retaining device for various kinds of swinging closures such as gates, garage doors and the like.

Into carrying the invention into effect, I have evolved and produced a simplified, economical and inexpensive device characterized by two primary parts; that is, an attaching block having an especially designed shouldered keeper, and a swingably mounted element functioning both as a cam and door lifting and releasing element.

The particular details and their relative arrangement and association will become more readily apparent from the following description and drawings.

In the drawings:

Figure 1 is a view showing the fragmentary portion of a building with a swingable door, and the improved door check and retaining device mounted at a spaced remote operating point.

Figure 2 is an elevational view showing the primary details of the invention with the door seated in the shouldered keeper.

Figure 3 is a front elevational view of the structure seen in Figure 2.

Figures 4 and 5 are cross sectional views taken approximately on the planes of the line 4—4 and 5—5 respectively of Figure 2.

Figure 6 is a perspective view of the primary factor of the invention.

In the drawings, in Figure 1, the reference character 7 designates what may be designated as a garage. The door is generally represented by the numeral 8 and the hinges by 9. The door is of an area less than the door opening and the hinges are such as to permit the door to be raised up slightly. In other words, these are flexible hinges.

The improved check and retaining device comprises three primary parts; namely, the anchoring post 10, the attaching block 11, and the swingably mounted cam and releasing element 12. The post is of any suitable configuration and is driven in the ground at a proper spaced point to be within the path of swinging motion of the door 8 as seen for example in Figure 1.

The block 12 which may be of any appropriate material and proportions includes a recess 13 formed in its top which constitutes a keeper seat for reception of the lower edge portion of the door 8 as seen in Figure 2. This recess has a relatively high abutment as at 14 forming a stop. In addition it has a relatively short extension or projection as at 15 forming similar front stop. In other words, there are front and rear stops at opposite ends of the keeper recess 13.

The block has recessed and slotted portions 16 and the slots serve to accommodate the headed ends and shank portions of the retaining bolts 17. These bolts pass through the block and through the post. This allows the block to be raised or lowered to render the operation of the check more sensitive.

The block also has an abutment pin as at 18. The movable element 12 comprises a disc-like portion 19 which is eccentrically pivoted through the medium of a bolt or the like as at 20 on the block 11. In addition, there is an outstanding tapered extension 21 which functions as a lever. The element 12 assumes, under normal conditions, the dotted line position shown in Figure 2, at which time the marginal or peripheral portion of the cam 19 is disposed to raise the door 8 over the projection 15 so that it will clear the projection and then drop down into the recess.

As the door swings over the cam, the lever portion 21 swings up to the full line position shown in Figure 2. This then disposes the cam in place so that by putting the foot on the lever 21, the operator can raise the door up and lift it out of the notch 13, and swing it clear of the projection 15 for releasing purposes. Hence the part 13 functions as a cam for seating the door as well as a releasing device for lifting the door out of the keeper notch.

It is thought that persons skilled in the art to which the invention relates will be able to obtain a clear understanding of the invention after considering the description in connection with the drawings. Therefore a more lengthy description is regarded as unnecessary.

Minor changes in shape, size, and arrangement of details coming within the field of invention claimed may be resorted to in actual practice if desired.

5 I claim:

1. In a door check and retaining device, a post, a block mounted thereon including a notch adapted to receive the lower edge portion of a swinging closure, an eccentric cam 10 pivotally mounted on said block and serving to seat the door in the notch, said cam having an extension functioning as a lever and said lever being arranged to permit the cam to be utilized as a releasing element for lifting the door up and out of the notch.
2. In a structure of the class described, a post, a block adjustably mounted thereon and having a keeper notch at its upper end, shoulder forming abutments associated with said 20 notch, an eccentrically pivoted cam carried by said block, said cam being located for co-operation with the front abutment and including an extension serving as a releasing lever.
3. As a new product of manufacture, a block having a notch in its upper end constituting a keeper seat and also including front and rear extensions defining shoulder abutments, said block having slotted portions 30 and fastening bolts whereby to permit it to be adjustably mounted on an anchoring post, an eccentrically pivoted cam carried by the block and having its peripheral portion associated with one of said abutments 35 said cam including an extension functioning as a foot lever.

In testimony whereof I affix my signature.

JOHN JACOB CISLER.
